A. J. MATTER & F. V. CONLEY,
SILENT CAMERA SHUTTER,
APPLICATION FILED MAY 18, 1917.

1,298,755.

Patented Apr. 1, 1919.

UNITED STATES PATENT OFFICE.

ALBERT J. MATTER AND FRED V. CONLEY, OF PORTLAND, OREGON.

SILENT CAMERA-SHUTTER.

1,298,755.

Specification of Letters Patent.

Patented Apr. 1, 1919.

Application filed May 18, 1917. Serial No. 169,597.

To all whom it may concern:

Be it known that we, ALBERT J. MATTER and FRED V. CONLEY, citizens of the United States, and residing at Portland, in the 5 county of Multnomah and State of Oregon, have invented certain new and useful Improvements in Silent Camera-Shutters, of which the following is a specification.

This invention relates to photographic 10 shutters and has for its object to provide a silent operating mechanism therefor.

We attain this object by means of the improvements illustrated in the accompanying drawings in which;

15 Figure 1 is an elevation of our improved shutter.

Fig. 2 is a bottom view of the shutter shown in Fig. 1, with the lower bearing plate removed and the operating engine and 20 operating-shaft bearing shown in cross-section.

Fig. 3 is a bottom view of the portion above the line A—A in Fig. 1, showing the shutter-closing spring and connecting rod.

25 Fig. 4 illustrates the method of attaching the engine to the shutter-board.

Fig. 5 is a detail bottom view of the focusing lock.

Like numerals of reference indicate similar parts throughout the several views.

Referring to the drawings, 1 indicates a shutter-board of the usual construction having an opening therethrough at 2. At the top and bottom of the shutter-board 1, are 35 attached bearing plates 3 and 4 respectively. The upper bearing plate 3 carries two ball-bearing cups 5 provided with steel balls 6. The lower bearing-plate 4 carries two bearing-cups 7 within which are disposed plungers 8 and springs 9 and they are further provided with steel balls 10. Shafts 12 and 13 carrying shutter-plates 14 and 15 respectively and having pivot ends as at 16 are 40 pivotally mounted between and within the upper and lower bearings as shown in Fig. 1.

To provide proper relative movement of the two shutter plates 14 and 15 their shafts 12 and 13 are respectively provided with connecting rod disks 17 and 18 which carry a 45 connecting rod 19 operatively mounted. Just below the shutter plates upon the shafts 12 and 13 are mounted the grooved disks 21 and 22 respectively, having spring grooves 23 within which a spring 24 is attached by 50 means of pins 25. This spring is for the purpose of keeping the shutter normally in

closed position and to prevent the plates from rattling when opening. Top and bottom plates 27 are provided to prevent light entering under the shutter plates 14 and 15. 60

To operate the shutter a crank disk is mounted upon the shaft 12 at 29 and carries the pivotally mounted end of a drive-shaft 30 which passes through a bearing 31 having a silent bushing 32. The drive shaft 65 30 is provided at its free end with a flat head 33. An operating engine is provided as shown in the various figures and consists of two convexed disks 35 and 36 provided respectively with an orifice 37 and a tube 70 projection 38 and attached at their peripheries by means of screws 39. A rubber disk 40 is held between the disks 35 and 36 and, secured therebetween by the screws 39. An operating tube is provided at 42 and is 75 equipped with the usual hand-bulb for forcing air between the rubber disk 40 and the disk 36. To facilitate renewal of the engine when desired, a locating plate is provided as at 43, being rigidly and permanently attached to the shutter board 1, and the engine is attached to said locating plate as by screws 44 which pass through attaching extensions 45 and 46 of the disks 35 and 36 respectively. It is now obvious that by forcing air through the tube 42 into the space between disk 40 and disk 36 said rubber disk 40 will exert pressure against the head 33 of the operating shaft 30 tending to rotate the crank-disk 29 thereby, in connection 80 with the connecting rod 19, forcing the shutter plates 14 and 15 into open position. To hold the shutter in open position when focusing, a focusing-lock is provided and comprises a latch 48 pivotally mounted, at 49 85 upon the shutter-board 1 and having a hook end 50 with a spring extension 51. A spring is provided at 53, attached at one end to the latch 48 and at its other end to the shutter board 1 thus providing means for holding 90 the latch out of engagement with the crank disk 29 which is provided with a notch at 54 to be engaged by the hook end 50 of said latch. To hold the latch in engagement with the crank disk an operating-cord is 105 provided at 55 passing through a bearing or guide 56 carried by the shutter board 1 and a spring 27 is attached, to one end of the cord 55 and to the spring extension of latch 48. Said spring 57 is stronger than spring 110 53 so that by pulling the cord 55 the latch is forced into resilient engagement with the

crank disk 29. In operation the cord 55 is first operated so as to hold the latch in locking engagement as described; the shutter operating bulb is then compressed so as to 5 open the shutter in order that the crank-disk 29 will be rotated into the position shown in Fig. 5 whereupon the latch will engage the notch 54 thus holding the shutter in open position for focusing and permitting 10 release of the bulb until ready to again operate the shutter. The cord 55 may now be released as the back pressure of the shutter through the medium of spring 24 will now hold the latch in engagement until the bulb 15 is again compressed, whereupon the spring 53 will release the latch and permit closure and free operation of the shutter.

What is claimed is;

1. A silent camera shutter comprising a 20 shutter-board having rigidly mounted pivotal shutter bearings in combination with resiliently mounted pivotal shutter bearings, shutter-plates pivotally mounted in and between said rigid and resilient bearings in 25 such manner as to prevent rattling movement in the bearings, means connecting the several shutter plates for simultaneous operation, a spring mounted so as to close the shutter and also create a tension in the bearing 30 ends of said connecting means so as to take up lost motion, an operating engine having a flexible diaphragm, pneumatic means for distending said diaphragm and means operatively connecting said diaphragm with said shutter-plates, all substantially as described and intended to provide a silently operable shutter.

2. In a silent shutter of the character described, a silent operating engine comprising 40 a perforated front plate, a concave back-plate having a tube connection, a diaphragm of sheet rubber interposed between said front- and back-plates which are so disposed as to form a chamber for the diaphragm, 45 means for fastening the front- and back-plates with the diaphragm interposed therebetween and a slidably mounted operating shaft having a head held in juxtaposition to said diaphragm but not in contact with said 50 diaphragm chamber and operatively connected at its opposite end with said shutter.

3. The combination with a shutter comprising plates carried by pivotally mounted shafts, one of which is provided with a crank-disk, of an operating shaft having one 55 end pivotally mounted in said crank-disk and its other end slidably mounted in a

padded bearing and provided with a button head, and means for exerting pressure against said button head tending to operate 60 the shutter plates.

4. The combination with a shutter comprising plates carried by pivotally mounted shafts, one of which is provided with a crank-disk, of an operating shaft having one 65 end pivotally mounted in said crank-disk and its other end slidably mounted in a padded bearing and provided with a button head, and an operating engine comprising a concave perforated front plate, a concave 70 back plate having a tube connection, a diaphragm of sheet rubber interposed between said front- and back-plates which are so disposed as to form a chamber for the diaphragm, means for fastening the front- and 75 back-plates with the diaphragm interposed therebetween and so disposed as to permit the said diaphragm to operate against said button head when air is forced in through the tube connection. 80

5. The combination with a shutter comprising plates carried by pivotally mounted shafts, one of which is provided with a crank-disk, of an operating shaft having one 85 end pivotally mounted in said crank disk and its other end slidably mounted in a padded bearing and provided with a button head, an operating engine comprising a concave perforated front plate, a concave back plate having a tube connection, a diaphragm 90 of sheet rubber interposed between said front- and back-plates which are so disposed as to form a chamber for said diaphragm, means for fastening the front- and back-plates with the diaphragm interposed there- 95 between and so disposed as to permit the said diaphragm to operate against said button head when air is forced in through the tube connection, and means for engaging and locking said operating mechanism when the 100 shutter is in open position.

6. The combination with a shutter comprising plates carried by pivotally mounted shafts, one of which is provided with a crank-disk of means adapted to engage said 105 crank disk for the purpose of locking it in open position.

In testimony whereof we affix our signatures in presence of two witnesses.
